UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,599, dated August 28, 1894.

Application filed July 31, 1894. Serial No. 519,105. Term of patent 8½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of an arrangement of sprays of flowers and leaves of roses and 10 daisies as represented in the accompanying drawing. The border or upper portion of the design is also formed of flowers and leaves of roses and daisies arranged in the form of open wreaths, with a group of said flowers and leaves in the center of said wreaths and connected by festoons formed of sprays of said flowers and leaves as shown in the drawing.

What I claim is—

1. The design for wall paper herein shown and described.

2. In the design for wall paper, the border herein shown and described.

Witness my hand this 28th day of July, 1894.

CHARLES BOOZE.
